UNITED STATES PATENT OFFICE.

GEORGE A. LOWRY, OF CHICAGO, ILLINOIS, ASSIGNOR TO THE PLANTERS
COMPRESS COMPANY, OF BOSTON, MASSACHUSETTS.

APPARATUS FOR COMPRESSING FIBROUS OR OTHER MATERIAL.

SPECIFICATION forming part of Letters Patent No. 680,874, dated August 8, 1898.

Application filed May 29, 1898. Serial No. 718,648. (No model.)

To all whom it may concern:

Be it known that I, GEORGE A. LOWRY, a citizen of the United States, residing at Chicago, in the county of Cook and State of Illinois, have invented a new and useful Apparatus for Compressing Fibrous or other Material, of which the following is a specification.

This invention relates to apparatus for compressing fibrous or other material.

10 The object of the invention is to improve the construction and arrangement of the slotted feed head or cap, whereby the feed of the material to be compressed may be regulated to suit the conditions and kinds of such material.

15 Other objects of the invention will appear more fully hereinafter.

20 The invention consists, substantially, in the construction, combination, location, and relative arrangement of parts, all as will be more fully hereinafter set forth, as shown in the accompanying drawings, and finally pointed out in the appended claims.

25 Referring to the accompanying drawings and to the various views and reference-signs appearing thereon, Figure 1 is a view, partly in elevation and partly in central section, of a compressing apparatus, showing a feed cap or head applied thereto. Fig. 2 is a top plan view of a form of cap or head embodying the principles of my invention. Fig. 2^a is a similar view of another form of cap or head embodying the principles of my invention. Fig. 3 is a similar view, somewhat in diagram, illustrating a slightly different arrangement

35 of feed-slots embraced within the scope of my invention. Fig. 4 is a view similar to Fig. 3, illustrating in diagram an arrangement where the slots are curved in the direction of their 40 length. Fig. 5 is a broken detail view in section on the line 5-5, Fig. 2. Fig. 6 is a detached detail view in plan of a plate or section employed in one form of cap or head embodying my invention. Fig. 7 is a similar view of

45 a strengthening-block. Figs. 8 and 8^a are diagrams illustrating the feeding action of the material through the feed-slots in the cap or head with different arrangements of slots. Figs. 9, 10, and 11 are views similar to Figs. 50 3 and 4, showing different arrangements of feed-slots in the cap or head. Fig. 12 is a

broken detail sectional view on the line 6-6, Fig. 2^a. Fig. 13 is a similar view on the line 7-7, Fig. 2^a.

The same part is designated by the same reference-sign wherever it occurs throughout the several views.

In my Patents Nos. 581,600 and 581,601, granted April 29, 1897, and in my pending application, Serial No. 682,947, filed June 8, 1898, I have described and claimed an apparatus for compressing cotton and other fibrous material in which is employed a chamber or holder open at both ends and a slotted cap or head for one end of said chamber, these parts being mounted for relative rotation. In the operation of a baling apparatus embodying these generic features the chamber is first filled by hand or otherwise to form a sufficient body. Then by imparting a relative rotation to the chamber and cap and supplying the material to be compressed to or adjacent to the slot or slots in the cap such material is caught or engaged by the material previously introduced into the chamber and is drawn into such chamber and compressed and formed into condensed spiral layers, the body of the material contained in the chamber being augmented endwise by each spiral layer thus added thereto and correspondingly advanced through the chamber, finally emerging from the chamber in the form of a column in a highly condensed or compressed state, and it is set forth in said patents and application that the relative rotation of the chamber and cap might be secured by rotating either one or both of these parts. The present invention relates to apparatus operating substantially as above set forth and embodies improvements in the construction of the cap or head and in the arrangement of the feed-slots therein.

Referring to the drawings, reference-sign A designates the chamber or holder open at both ends, and B designates generally the slotted cap or head. These parts are mounted for relative movement. For instance, in the particular form shown the chamber is mounted for rotation and is rotated through gear C from any suitable source of power, while the slotted cap is held stationary upon the supporting-framework.

The first feature of my invention to which reference will be made is the providing of a plurality of slots in the cap or head. I have found that by providing the cap or head with 5 a plurality of slots instead of one and through each of which material is supplied to the chamber or holder not only is the capacity of the machine multiplied in accordance with the increase in the number of slots, but such 10 capacity is multiplied without any perceptible increase in the power required to run the machine and without additional wear upon the cap and at the same time maintaining or producing in the machine substantially the same degree of compression as if only one or 15 two slots were employed. Moreover, in a machine employing a plurality of slots in the cap through each of which material is introduced to the machine the material is constantly added to the mass contained in the chamber or holder in several distinct separate 20 layers. Consequently the length of time during and the distance through which each layer travels in contact with the under surface of 25 the cap is only a small fraction of the time or distance of travel of such material in contact with such surface in the case of a single slot—that is, each layer introduced through any particular slot bears upon the under surface of the cap only until it arrives adjacent to the next slot, where a new layer of material is introduced between the under surface of the cap and the first-mentioned layer. Therefore before any particular layer can 30 acquire an undesirable degree of heat through frictional contact with the under surface of the cap it is covered by a new layer of material introduced through the next slot, which new layer of material is cool, and therefore 35 tends to prevent the excessive heating that would result if the first layer of the compressed material were carried all the way around in contact with the under surface of the cap. Thus the cap is kept cool and the 40 use of a water-jacket or other cooling device is avoided. In the drawings I have indicated a plurality of slots in accordance with the principles of my invention. The slots may 45 be formed through a solid plate or cap, as indicated in Fig. 2^a, or they may be formed by special constructions and arrangements of the cap, as will be more fully hereinafter described.

The next feature of my invention to which 55 reference will now be made is the arrangement of the slots in the cap or head with reference to the relative movement of the chamber and cap—that is, with reference to the line of travel of the material past the slots 60 in the case where the chamber or holder rotates or the line of travel of the slots past or over the material in the case where the cap rotates. I have found that the arrangement of the slots with reference to this relative 65 movement plays an important part in the feed of the material therethrough and in the distribution thereof in the formation of the

bale. For instance, I have found that in the case where the chamber revolves and the cap is held stationary, which is the arrangement 70 illustrated, if the inner ends of the slots—that is, the ends nearest the center of the cap—terminate at a point to the right of the center—as shown, for instance, in Figs. 2^a, 8^a, 10, and 11—then every point in the surface of the 75 material contained in the chamber which is in contact with the under surface of the cap travels past each slot in a line the direction or trend of which is toward the inner end of the slot—that is, toward the axial center of the chamber—it being understood that all points of the surface of the material, under the condition stated, move in lines concentric with the axis of rotation of the chamber. This result is indicated in Fig. 8^a, where 80 in the arrows or lines crossing the slots a indicate the direction and line of travel of the material past the slots, and from an inspection of these crossing arrows and lines it will be seen that the direction or trend thereof is 85 toward the inner ends of said slots. Since the feed of the material to the chamber is effected by reason of the material previously introduced thereto catching or engaging the additional material supplied adjacent to the slots 90 in the cap or head, and thereby exerting a drawing action thereon to draw the same into the chamber in the form of a thin condensed layer or sheet, it will be seen that in the arrangement of slots as above described—that 95 is, slots having their inner ends terminating on the right-hand side of the center of the cap—the direction or trend of the draw or feed of the material through the slot is from the outer and toward the inner end of such slot. The effect of this is to tend to carry the material toward the center of the bale. If, however, the inner ends of the slots terminate at 100 a point to the left-hand side of the center of the cap—that is, on the near side thereof with reference to the direction of travel of the material, as indicated in Figs. 2, 3, 4, and 8—then every point in the surface of the material contained in the chamber which is in contact with the under surface of the cap, which, 105 moving in lines or circles concentric with the axis or rotation of the chamber, travels past the slot in a line the direction or trend of which is toward the outer end of the slot—that is, the end of the slot farthest from the 110 axial center of the chamber. This trend is indicated by the lines or arrows shown crossing the slots a in Fig. 8. The effect of this trend in the drawing action exerted upon the material while being fed into the machine 115 through the slots is to cause the same to draw toward the outer end of the slot and away from the center or axis of rotation of the chamber. If the slots are arranged truly radial to the center of the cap, the trend in the 120 drawing action is neither toward nor away from the center, for the reason that all points in the surface of the material which moves in contact with the inner surface of the cap 125 130

travel in circles concentric with the axis of rotation of the chamber, and hence in lines normal or at right angles to the radial slots.

From the foregoing description it will be seen that by varying the position of the slot or slots, so that they are more or less inclined in one or the other direction with relation to the line of travel of the material across it, I am enabled to vary the trend or direction of feed of the material through the slots, as may be desired, to suit different kinds, natures, conditions, or qualities of material. It will also be seen that when the slots terminate at their inner ends on one side of the center or axis of rotation of the material and extend therefrom at an angle to a radius of the cap passing through the outer end of said slot the trend of draw is in one direction—that is, toward or away from the center, as the case may be—while if such slots terminate on the opposite side of the center or axis then the trend of draw or feed is in the opposite direction. This crowding or trend of draw of the material will be readily understood upon inspection of the diagrams Figs. 8 and 8^a. As indicated in Fig. 8, it will be seen that the line of travel of the material across the slot is somewhat diagonal with respect to the slot—that is, take any particular point in the surface of the material and it approaches the near edge of the slot at a point nearer the inner end thereof than that at which it leaves the far edge—whereas the reverse of this is the case in Fig. 8^a, and by carrying the angle of the slot with reference to the line of travel of the material the draw of the material is correspondingly varied, the medial position being attained when the slot is truly radial. It will also be seen that by this arrangement the distribution of the material through the slots is also regulated. In the foregoing description I have located the inner ends of the slots with reference to the center of the cap—that is, as being on the right-hand or far side or on the left-hand or near side of such center with reference to the line of travel of the material. This idea may be expressed in a way such as to apply generally to the location of the slots, whether terminating on one side or the other of the center—as, for instance, by saying that the slots are inclined to a plane at right angles to the line of travel of the material—that is, inclined to a radius of the cap passing through the outer end of the slot—this expression being intended to describe the location of the slots whether terminating on one side or the other of the center of the cap—that is, whether the trend of the draw of the material is toward or away from the center. Of course other language may be employed to describe the same idea, and I do not desire to be limited or restricted by the particular form of expression employed, as it is intended to cover and include, broadly, the idea set forth, whether expressed in one or another form of language.

The trend of the drawing action upon the

material while being introduced through the slots, as above explained, I have found to be the same—that is, either toward or away from the center of the chamber or holder, according as the slots terminate at their inner ends on one side or the other of the center—whether such slots are straight, as shown in Figs. 2, 2^a, 3, 9, and 10, or whether they are curved in the direction of their length; as shown in Figs. 4 and 11, the arrows indicating the direction or trend of such draw.

By reason of the increasing radius of the circles or travel of the surface of the material toward the outer ends of the slots it will be seen that in the case of slots which are straight throughout their length the angle of travel of the material past the slots and relative thereto varies, such lines of travel intersecting the slots more acutely nearer the center or axis of rotation and less acutely toward the outer ends of the slots, or, to express the same idea in another way, the slots when inclined, as above described, and terminating on one side or the other of the center or axis of rotation are more nearly tangential at their inner ends to the circles or lines of travel of the material and are more nearly normal or at right angles to such lines of travel at their outer ends, thus giving a varying drawing or distributing effect at different points in the length of the slot. If, however, it is desired to maintain the angle of the slot to the path of travel of the material substantially constant throughout the length of the slot, then the curved slots may be employed.

In the foregoing description I have described the invention as applied in the case where the chamber or holder rotates and the cap is held stationary. The same principles apply in the case where the chamber or holder is stationary and the cap revolves. Where the chamber is stationary and the cap revolves in a direction opposite to that in which the chamber revolves, as above described, the slots occupy the same relative positions as explained above with reference to the revolving chamber; but if it may be desired to revolve the cap in the same direction as that above described with reference to the chamber. In such case the slots will occupy the reverse positions with respect to those above described—that is, where it is desired that the trend of the drawing action exerted upon the material to feed the same through the slots is to be outwardly from the center, then the slots should terminate on the right-hand side of the center of the rotating cap, and if it is desired that such trend be toward the center then the slots should terminate at a point on the left-hand side of the center of the cap. In practice I prefer to employ a rotating chamber and a stationary cap and that the slots in the cap terminate at their inner ends at a point to the left of the center of the cap.

In Fig. 2^a I have shown the slots formed in a solid cap. In other views of the drawings I have shown a different construction of cap,

which possesses desirable advantages and which is included in the scope of my invention.

In the operation of a compressing apparatus of the class to which this invention relates and as above explained the material to be compressed is supplied adjacent to the slots in the cap and is caught or engaged by the mass of material in the chamber and drawn through the slots in a thin sheet or layer. Now in order that the material may be brought into sufficiently close proximity to the surface of the mass of material within the chamber or holder to be efficiently caught or engaged thereby it is desirable that the cap be made as thin as possible, and since the cap operates as an abutment for one end of the mass of material contained in the chamber, and hence plays an important part in the operation of advancing and compressing the material, it will be seen that it is necessary to so construct the cap that it will efficiently withstand the wear and strains imposed thereon. In order to provide a construction where these objects are attained in an economical and efficient manner, I may, if desired and as shown in Figs. 2, 3, 4, 6, 7, 9, 10, and 11, form the cap in sections. To this end I provide the comparatively thin plates or sections F, so relatively arranged as when assembled edge to edge to form a cap or head to completely cover the open end of the chamber or holder. These sections or plates are assembled edge to edge to form the cap, the edge of one section being suitably formed—as, for instance, with projections or shoulders G— to fit in corresponding seats or rabbets H, (see Fig. 6,) formed on the approximate edge of the adjacent section or plate, thereby suitably offsetting said edges to leave the feed-slot a therebetween. That edge of the section or plate which constitutes the near edge of the slot may, if desired, be suitably rounded or beveled off, as shown at b, Figs. 5 and 6, to facilitate the passage of the material into and through the slot. Similarly, to secure best results the under surface of that edge of a section or plate which constitutes the far edge or compressing-lip of the slot is rounded, beveled, or inclined toward the under surface of the plate or section, thereby forming a contracting throat, as shown at c, this also aiding and facilitating the feed of the material through the slot and the condensation thereof into a thin sheet or layer. The shape of the meeting edges of the sections or plates may be varied according to whether it is desired to form straight or curved slots, as clearly shown in the drawings, and when said plates or sections are suitably assembled they may be secured in proper position and relation, as by means of the bolts M, to the framework or to an annular frame K, which is in turn bolted or secured to the framework in the case where the cap revolves. In thus forming the cap in sections they may be made comparatively thin, thus enabling the material to

be brought into close proximity to the mass contained in the chamber, and hence insuring an entangling of the fibers of the material to be fed with those of the material in the chamber, thus insuring an efficient feed thereof through the slots. Moreover, by making the sections or plates in duplicate of each other in case of breakage repairs may be easily and expeditiously made by replacing the broken section or plate without necessitating replacement of the entire cap. In order to efficiently brace the sections or plates of the cap and to give them sufficient rigidity and strength to resist the pressure exerted thereon, I may provide the brace-blocks L and suitably bolt or otherwise secure the same upon the sections or plates. In the form shown the securing-bolts M, by which the sections or plates are fastened to the framing or to the spider K, are also arranged to pass through the brace-blocks, thus securely bolting the brace-blocks or ribs to the plates or sections. The ends of the brace-blocks presented toward the center of the cap should be somewhat tapered and rounded or beveled off at the sides, as indicated at f g, in order that the material supplied to the cap may be permitted to approach into close proximity to the slots.

It will be observed that the slots a do not extend entirely to the center of the cap, and hence undue twisting of the material at the center of the bale is avoided and the cap is not unduly weakened at that point. This arrangement also results in the formation of a longitudinal central opening at the axis or middle of the bale, and, if desired, an opening, as indicated at J, may be provided at the center of the cap, thus affording access to the central hole or opening through the bale. The slots a preferably extend toward the periphery of the cap a distance such as to expose the inner surface or wall of the chamber, and they should also be sufficiently narrow in transverse width or dimension to prevent the compressed material contained in the chamber or holder from raising therein, so as to form a shoulder or ridge between the lips of the slot high enough to offer undue resistance to the relative movement of the chamber and cap or to prevent the ready entrance of the loose material into and through the slot. This width is in practice varied within certain limits according to the length of fiber of the material being compressed and the degree of density. A comparatively narrow slot facilitates a high degree of compression of the material. Thus far in practice my experiments have indicated that the slots should be from about one-quarter to about three-quarters of an inch in width. With what is known as "short staple" or "upland" cotton about nine-sixteenths of an inch has been found satisfactory.

By rounding or beveling the sides or brace ribs or blocks L, as at f g, or by beveling or inclining the surface of the sections F of the cap or of the surface of a solid cap, as at b² b³,

Fig. 12 and 13, on opposite sides of the slots it will be seen that the material supplied to the cap is directed toward the slot and into proximity to the surface of material in the chamber, as above explained, thus facilitating the engagement of the loose material by the material in the chamber, and hence insuring an efficient feed.

Many specifically different arrangements may be devised for accomplishing the desired objects above noted, and many variations and changes in the details of construction and arrangement would readily suggest themselves to persons skilled in the art and still fall within the spirit and scope of my invention. I do not desire, therefore, to be limited or restricted to the exact construction, arrangement, and details shown and described as illustrative of operative embodiments of the principles of my invention; but,

Having now set forth the object and nature of my invention and various constructions and arrangements embodying the principles thereof and having described such constructions and arrangements, their purposes, functions, and modes of operation, what I claim as new and useful and of my own invention, and desire to secure by Letters Patent of the United States, is—

30 1. In a machine for compressing fibrous or other material, a chamber or holder for the compressed material, a cap for one end of said chamber, said cap forming an abutment for the compressed material, means for relatively moving said chamber and cap, said cap provided with a plurality of slots therein, as and for the purpose set forth.

2. In a machine for compressing fibrous or other material, a chamber or holder for the compressed material, a cap for one end of said chamber, said cap forming an abutment for the compressed material, means for relatively moving said chamber and cap, said cap provided with a plurality of slots therein, the compressing edge of each slot being inclined toward the inner surface of the cap, as and for the purpose set forth.

3. In a machine for compressing fibrous or other material, the combination with a chamber, of a cap for one end thereof, said cap provided with one or more openings or slots, each of which is inclined to a radius of the cap running from the outer end of the slot to the center of the cap, and means for relatively rotating said chamber and cap, as and for the purpose set forth.

4. In a machine of the class described, the combination with a chamber or holder, of a cap for one end thereof, said cap provided with one or more slots, the inner ends of said slots terminating at a point to one side of the center of the cap relative to a radius or radii passing through the outer end of said slot or slots, and means for relatively rotating said chamber and cap, as and for the purpose set forth.

5. In a machine for compressing fibrous or

other material, a cap or abutment, and means for rotating the mass of compressed material in contact therewith, said abutments being 70 provided with one or more slots extending from near the middle to near the periphery thereof, said slots being inclined to the path of travel of the compressed material past them, to effect the desired distribution of the 75 material entering the slots, substantially as and for the purpose set forth.

6. In a machine for compressing fibrous material, a chamber or holder for the mass of compressed material, a cap or head, against 80 the inner surface of which one end of the compressed material contained in said holder contacts, said cap provided with one or more slots, the width between the lips of which is insufficient to permit the compressed material to rise therein, and the under surface of the compressing edge of which is inclined toward the under surface of said cap, the outer surface of the cap on each side of each slot being inclined toward said slot, and means 85 for causing a relative movement of the cap and chamber, substantially as and for the purpose set forth.

7. In a machine for compressing fibrous material, a chamber or holder, a cap having 90 one or more openings or slots formed therein, the outer surface of said cap on opposite sides of each slot or opening being inclined toward said slot or opening, and means for relatively rotating said chamber and cap, as and for the 100 purpose set forth.

8. A machine for compressing fibrous material comprising a chamber forming a holder for the compressed material, a cap for one end of said chamber forming an abutment 105 for the compressed material therein, means for producing rotary movement of one of said elements relative to the other, said cap being provided with a plurality of inlet-openings, each in the form of a slot, the compressing 110 edge of each inlet-slot being inclined toward the inner surface of said cap and the outer surface of the cap converging toward the edges of each inlet-slot, substantially as and for the purpose set forth.

115 9. In a machine for compressing fibrous material, a chamber, a cap having an opening or slot therein, the outer surface of said cap on opposite sides of said slot being inclined toward said slot, and the compressing edge or lip of said slot being inclined toward the inner surface of said cap, and means for relatively rotating said chamber and cap, as and for the purpose set forth.

120 10. In a machine of the class described, the combination with a chamber or holder, of a cap for one end thereof, said cap provided with one or more slots, each arranged to one side of a radius drawn from the center of the cap to the outer end of said slot, and means 130 for relatively rotating said chamber and cap, as and for the purpose set forth.

11. In a machine of the class described, the combination with a chamber, of a cap for one

end thereof, said cap having one or more slots therein, each slot terminating at its inner end at a point on the left-hand side of the center of the cap, and means for relatively locating said chamber and cap, as and for the purpose set forth.

12. In a machine of the class described, a chamber, a cap for one end thereof, said cap provided with one or more slots, said slots being curved in the direction of the length thereof, and means for relatively rotating said cap and chamber, as and for the purpose set forth.

13. In a machine of the class described, a chamber, a cap for one end thereof, said cap made in sections, and means for relatively rotating said cap and chamber, as and for the purpose set forth.

14. In a machine of the class described, a chamber, a cap for one end of said chamber, said cap composed of sections arranged edge to edge and offset from each other to form feed-slots and means for relatively rotating said chamber and cap, as and for the purpose set forth.

15. In a machine of the class described, a chamber, a cap for one end of said chamber, said cap composed of a series of thin plates arranged edge to edge and offset from each other to form feed-slots therethrough, strengthening blocks or braces secured to said sections or plates, and means for relatively rotating said chamber and cap, as and for the purpose set forth.

16. In an apparatus of the class described, a feed-cap comprising plates or sections arranged edge to edge and having their inner

ends presenting toward a common center, means for securing said ends together, said plates or sections being offset from each other to form feed-slots, as and for the purpose set forth.

17. In a machine for compressing fibrous material, a cap or abutment, and means for rotating a mass of compressed material in contact therewith, said abutment being composed of a main annular frame or head, and a plate composed of a number of sections, each securely fastened to said annular frame, the edges of said sections being formed to produce slots in the plate or cover composed of said sections, substantially as and for the purpose set forth.

18. In a machine for compressing fibrous material, a cap or abutment, and means for rotating a mass of compressed material in contact therewith, said abutment being composed of a main annular frame or head, and a plate composed of a number of sections, each securely fastened to said annular frame, the edges of said sections being formed to produce slots in the plate or cover composed of said sections, and reinforcing blocks or ribs overlying said sections of the cap-plate, substantially as described.

In witness whereof I have hereunto set my hand, this 27th day of May, 1899, in the presence of the subscribing witnesses.

GEORGE A. LOWRY.
